DESIGN FOR AN ILLUMINATING RADIO CABINET

George A. Stamm, Lincoln Township,
Berrien County, Mich.

Application April 18, 1936, Serial No. 62,203

Term of patent 7 years

To all whom it may concern:

Be it known that I, George A. Stamm, a citizen of the United States, residing in Lincoln Township in the county of Berrien, State of Michigan, have invented a new, original, and ornamental Design for an Illuminating Radio Cabinet, of which the following is a specification, reference being had to the accompanying drawing, forming a part thereof.

Figure 1 is a view of an illuminating radio cabinet in front elevation, showing my new design;

Figure 2 is a side view thereof; and
Figure 3 is a perspective view.

The rectangular panels in the radio cabinet which are shaded like glass represent light emitting elements.

I claim:

The ornamental design for an illuminating radio cabinet as shown and described.

GEORGE A. STAMM.
